UNITED STATES PATENT OFFICE.

WALLACE McC. WHITE, OF BURLINGTON, IOWA, AND WILLIAM A. WHITE,
OF ROCK ISLAND, ILLINOIS.

APPARATUS FOR PLACING RAILROAD-TORPEDOES.

SPECIFICATION forming part of Letters Patent No. 250,179, dated November 29, 1881.

Application filed October 22, 1880. (No model.)

To all whom it may concern:

Be it known that we, WALLACE McC. WHITE and WILLIAM A. WHITE, citizens of the United States, residing, respectively, at 5 Burlington, in the county of Des Moines and State of Iowa, and at Rock Island, in the county of Rock Island and State of Illinois, have invented a new and useful apparatus for placing, holding in place, and holding to the 10 rails when placed thereon, railroad-torpedoes, of which the following is a specification.

Our invention relates to the manner of handling railroad-torpedoes and holding them in a 15 handle ready for use, by means of which they can be attached to the rail from the rear end of the train or car while the same is moving; and it consists of a handle with springs and protectors attached.

The objects of our invention are, first, to 20 provide a handle in which the torpedo can be placed ready for use at any time, and by means of which they can be readily attached to the rail and firmly held thereto by means of springs attached to the torpedo; and, second, to provide an apparatus by which such 25 torpedoes may be placed on the rail from the rear end of a train or car while moving, thus avoiding the necessity of stopping the train for that purpose, whereby a great saving both 30 of time and expense will result therefrom. We attain these objects by means of the mechanism illustrated in the accompanying drawings, in which—

Figure 1 is a perspective view of a rail with 35 our improvement applied thereto. Fig. 2 is a reverse-plan view of our improvement. Figs. 3 and 4 are side views thereof, and Fig. 5 shows a torpedo attached to the rail after the handle has been withdrawn therefrom.

Similar letters refer to similar parts throughout the several views.

To the torpedo D are attached two (2) metal 40 springs, E E, on each side thereof, which extend below the torpedo and so curved and shaped as to hold it firmly to the rail when once placed thereon, and to prevent it from becoming de-

tached from the rail after it is placed thereon and while it is being disconnected from the handle, as shown in Figs. 5 and 1.

The handle C is constructed of wood or other 50 material of convenient length and size, depending upon the circumstances under which it is to be used and the size of the torpedo used. To the lower end of said handle C, and on each side thereof, are attached two (2) metal springs, 55 B B, each extending below or projecting beyond the end of the handle a sufficient distance to hold the torpedo between them and firmly against the end of the handle, as shown in Figs. 1 and 2. On the outside of these two 60 (2) metal springs B B are placed two (2) metal protectors, F F, to prevent their striking the rail when placing the torpedo on the rail. Between the two springs B B and the protectors F F, on each side of the handle, are also attached 65 two (2) metal protectors, A A, so constructed as to allow the springs E E, attached to the torpedoes, to move in the open space in each protector, as shown in Fig. 1, and also for the purpose of preventing the springs B B, attached to 70 the handle, and the springs E E, attached to the torpedo, from becoming injured by accidentally coming in contact with the rail while the torpedo is being attached to it, and also to prevent the 75 torpedo from being disconnected from the handle while not in use and while it is being attached to the rail. Said protectors A A and F F are also so constructed as to prevent the torpedo from striking the rail and being exploded while being attached thereto. 80

Around the handle, and on the outside of the protectors A A and F F and the springs B B, is placed a band or ferrule, G, a similar band or ferrule, H, embracing the same parts, except F F, all for the purpose of holding them 85 more firmly to the lower end of the handle. They are for no other purpose, and may not be found to be necessary for that purpose.

We are aware that it is not new to provide a torpedo with a spring to attach it to the rail, 90 as shown, and also that we are not the first to provide a device whereby torpedoes may be

placed on the rails of a road while the train is in motion; hence we make no broad claim to these features; but

What we claim as new, and desire to secure
5 by Letters Patent, is—

1. The combination, with a handle, C, of
the springs B B, and guards A A and F F,
constructed and arranged as and for the pur-
pose set forth.

10 2. The combination, with the handle C, the

springs B B, and guards F F, of the ferrules
or bands G H, substantially as set forth.

WALLACE McC. WHITE.

WILLIAM A. WHITE.
